UNITED STATES PATENT OFFICE.

GEORGE HOWARD DAVOL, OF NEW YORK, N. Y.

SANDING ROLLER.

Application filed July 6, 1925. Serial No. 41,820.

This invention relates to what are termed sanding rollers and has for an object to provide an improved construction which may be used for receiving sandpaper, emery paper, buffing material or other members used in sanding, polishing, buffing or otherwise treating articles to shape the same and finish the same in a desired way.

Another object of the invention is to provide a roller which may receive sheet members for use in finishing articles, the structure being such that the sheet member is first grasped and then tightened so as to snugly fit the roller during the operation of the roller.

A still further object of the invention is to provide a roller which is adapted to be rapidly rotated when in operation, the construction being such that sandpaper or other material may be mounted thereon and pulled tightly in place through the use of a pair of rotatable gripping members which will not only pinch the ends of the sandpaper but will also pull adjacent edges of the sandpaper to cause the sandpaper to snugly fit the roller and thereby present a tight even surface.

In the accompanying drawings—

Figure 1 is an elevation of a roller, disclosing an embodiment of the invention.

Figure 2 is a sectional view through Figure 1 on line 2—2, the same being on an enlarged scale.

Figure 3 is a sectional view through Figure 2 on line 3—3.

Figure 4 is a sectional view through Figure 2 on line 4—4.

Figure 5 is a sectional view through Figure 2 on line 5—5.

Figure 6 is an enlarged longitudinal sectional view through turning and locking mechanism embodying certain features of the invention.

Figure 7 is an enlarged fragmentary sectional view through Figure 1, approximately on line 7—7, the same showing how the parts are positioned when the sandpaper or other article is first applied.

Figure 8 is a view similar to Figure 7 but showing the gripping members in gripping position with the parts rotated for pulling the sandpaper tightly against the roller.

Figure 9 is an elevation of a modified

form of clamping structure to that shown in Figure 6.

Figure 10 is a sectional view through Figure 9 on line 10—10.

Figure 11 is a sectional view through Figure 9 on line 11—11.

Referring to the accompanying drawing by numerals, 1 indicates a shaft of any desired kind, preferably provided with a tapering end 2 whereby it may be fitted into a chuck or other device for rotating the roller 3. The roller 3 is provided with a body 4 preferably of wood and with cup-shaped end members 5 and 6. These end members are preferably made from metal and are held in place by screws or other suitable means. Covering plates 7 and 8 are provided for the end members 5 and 6, said covering plates being provided with apertures 9 and 10. The shaft 1 is provided with an enlargement or collar 11 near one end and with a nut 12 at the opposite end. Whenever nut 12 is screwed down tight it will cause the end plates or covering members 7 and 8 to be firmly clamped against the end members 5 and 6 whereby upon the rotation of the shaft 1 the entire roller 3 will be rotated. Preferably the contact between plates 7 and 8 and the respective ends 5 and 6 is such that one part will be driven by the other through the action of friction though if desired, fastening means could be provided and also if desired, a key or other fastening means could be provided for connecting shaft 1 with body 4.

As indicated particularly in Figure 4, the body 4 is provided with a bore 13 through which the shaft 1 extends, a bore 14 through which the clamping structure 15 extends and a slot 16 for permitting the insertion of the ends of sandpaper or other desired member 17 as shown in Figures 7 and 8. In order to provide a somewhat yielding surface, a covering 4' of felt or other desired material is mounted on the body 4 and secured thereto by any suitable form of adhesive, said covering stopping at the slot 16 whereby the same is left completely exposed for its full length as shown in Figure 1. This slot is preferably the full length of the body 4 but does not extend through the end members 5 and 6.

As shown in Figure 4, the clamping struc-

ture 15 is of less diameter than the bore 14 whereby when sandpaper or other material 17 is inserted as shown in Figure 5, it may be grasped and then pulled to the position 5 shown in Figure 8, or if desired, may be pulled to a greater extent whereby the portion of the member 17 encircling the roller will be caused to tightly hug the roller and thereby present a very efficient abrading, 10 polishing or buffing surface according to the character of the member 17. The clamping structure 15 is provided with a tubular shell or casing 18 and removable end members 19 and 20, said end members being held in 15 place by suitable screws. The end member 20 is provided with a ratchet wheel 21 which may be integral therewith or may be made separate and rigidly secured thereto. Each 20 of the end members is provided with a bore accommodating the shaft 22, which shaft 22 adjacent the end member 19 is provided with a squared portion 23 for receiving the thumb member 24, said thumb member being adapted to be held in position by friction. A pair 25 of cams or eccentrics 25 and 26 are rigidly secured to the shaft 22 in any desired manner, as for instance, by being soldered or keyed thereto. These cams act on the movable gripping jaw 27, which gripping jaw 30 co-acts with a stationary gripping jaw 28 secured to the shell 18 in any suitable manner, as for instance, by the screws 29. The stationary jaw 28 is provided with a number 35 of longitudinally arranged teeth or raised portions 30, 31 and 32 while the movable jaw 27 is provided with two raised portions 33 and 34, said last mentioned raised portion fitting into the space between the raised portions of the stationary jaw whereby the 40 jaws may firmly grip the end portions 35 and 36 of the member 17 as shown in Figure 8. The ends of member 17 are inserted as shown in Figure 7 and then the shaft 22 turned until the jaws are closed as shown in 45 Figure 6. After this has been done, the shell 18 and associated parts are rotated by placing a key or other instrument on the squared end 37 of the end member 20 and then causing a rotation of the parts until 50 member 17 is as tight as desired. If preferred, the end 37 may be provided with a kerf for receiving a screw driver.

In order that the jaws 27 and 28 may be 55 opened whenever it is desired to insert the ends of member 17 or to remove member 17, springs 38 and 39 are provided and preferably secured in any desired manner to the stationary jaw 28 with one end pressing against jaw 27 in such a direction as to 60 cause the jaws to move apart. Pins 40 and 41 are provided to guide jaw 27 in its back and forth movement. By this construction and arrangement, whenever the cams 25 and 26 are moved to the position shown in Figure 7, the springs 38 and 39 will move the

jaws to an open position. When shaft 22 is rotated until the cams are in the position shown in Figures 6 and 8, the movable jaws will be moved to a closed position against the action of springs 38 and 39. In order 70 that the casing 18 may be of minimum size, the same is cut away at 25' and 26' in order to permit the cams 25 and 26 to swing through the casing when the jaws are to be opened. 75

It will be readily seen from Figure 8 that the bore 14 is of ample size to receive part of the ends 35 and 36 as they are wound around the casing 18. In order to prevent the casing 18 from unwinding or a reverse movement, a ratchet wheel 21 co-acts with a spring pressed pawl 42 carried by the end member 6. A swinging release member 43 is carried by the end 6 and is provided with a kerf 44 for receiving a screw driver whereby member 43 may be turned to move the pawl 42 to an open position against the action of spring 45. This will permit the ratchet wheel 21 and associated parts to rotate in a reverse direction and thereby permit the ends 35 and 36 to be readily removed. 85 90

Figures 9, 10 and 11 disclose a modified construction wherein the casing 18 is eliminated and the body is made into two parts, namely, sections 46 and 47. The section 46 95 is provided with a longitudinally positioned groove 48 adapted to receive the longitudinally positioned tooth or bead 49 formed on the section 47. In addition, section 47 is provided with a bore 50 adapted to accommodate the rod 51 which acts as an eccentric or cam. In order to cause the rod 51 to function in this manner, shaft 22' is eccentrically mounted in the rod or cam 51 and extends beyond each end thereof so that one 100 end is journaled in the bar 52 and part of the end 20 while the opposite end is journaled in the bar 53 and the end 19. By reason of this construction, whenever the shaft 22' is rotated, cam 51 will be rotated 105 and thereby cause the section 47 to move toward or from section 46 for clamping or releasing member 17. After the ends of member 17 have been gripped, the entire 110 structure may be rotated as in the preferred form so as to tighten the member 17 on the covering pad 4'. 115

The term "sanding roller" is intended to cover a roller of the kind described which is adapted to receive sandpaper, emery cloth, 120 polishing cloth, buffing leather or other material or in fact, any sheet material which is used to finish or work upon an article to get the same in the desired shape or condition. 125

What I claim is:

In a sanding roller a gripping structure for gripping a sheet of abrading or polishing material, said gripping structure including a pair of jaws, one jaw being sta- 130

tionary and the other movable, a looped spring carried by said jaws at each end, said springs acting to force the movable jaw from the stationary jaw, each of said springs having a slot, said movable jaw having an aperture adjacent each of said slots, a pin carried by the stationary jaw at each end and extending through the respective slots and through the respective apertures for guiding the movable jaw and the springs ¹⁰ as they function, and a manually actuated rotatable cam for causing the movable jaw to be closed against the action of said springs.

GEORGE HOWARD DAVOL.
